UNITED STATES PATENT OFFICE.

CARL SCHÖNFELD, OF MUNICH, GERMANY, ASSIGNOR TO ARTHUR KIEHNLE, OF PFORZHEIM, GERMANY.

CIGARETTE HOLDER.

Application filed December 8, 1927, Serial No. 238,702, and in Germany July 27, 1927.

This invention relates to a cigarette-holder.

The novelty consists in that on the sleeve, forming the cigarette-holder proper, i. e. designed to hold the cigarette, another sleeve is shiftably arranged so that it can be pulled as protecting tube over the portion of the cigarette projecting from the holder and over the glowing end of the same.

10 When the smoker wants to lay aside the lighted cigarette, he shifts merely the protecting tube over the the same such a distance that the lighted end is just covered. The support is not damaged, even when it 15 consists of inflammable material like a wooden-table—plate or a table-cloth. In this perfectly covered state the cigarette continues to burn a certain time and it can be smoked again when the protecting tube 20 has been pushed back. When, however, the cigarette is covered so that the glowing point is farther down in the protecting tube, access of the air is prevented and extinguishing takes place immediately. A smokable 25 remainder remains consequently still in the holder. The protecting tube has to be pushed back before the relighting and smoking of the cigarette. The protecting tube pushed over the cigarette serves therefore 30 also to prevent the fag-end of the cigarette from continuing to glow or from glowing after it has been laid down, whereby to the smoker the losses are saved, which were hitherto connected with the putting down 35 of the cigarette.

An embodiment of the invention is illustrated, by way of example, in the accompanying drawing in which:—

Fig. 1 is a longitudinal section showing 40 the improved cigarette-holder.

Fig. 2 is a top-plan-view of Fig. 1.

The cigarette-holder, according to the invention, consists of a sleeve *a* for holding the cigarette, of a protecting tube *b*, and of an outer guide-sleeve *c* for the protecting 45 tube *b*. The sleeves *a* and *c* are connected the one with the other at the mouth-piece-end by a short tube *d* which serves at the same time as guide for the mouth-piece *f* which is constructed to serve as cigarette-ejector. The tube *b* shiftably mounted 50 between the sleeves *a* and *c* and made of incombustible material has a projection *g* which projects in outward direction through a longitudinal slot *b'* of the outer sleeve *c* 55 and makes it possible to shift the protecting tube *b*.

The cross-section of the sleeve may be circular, oval or cornered. It is further possible to adapt the length of the protecting 60 tube to any cigarette length, so that even the longest cigarette may be covered.

I claim:

1. A cigarette-holder, comprising in combination a sleeve forming the holder proper, 65 a tubular mouth-piece shiftably mounted in said sleeve, a protecting tube shiftably mounted on said holder-sleeve, an outer protecting tube enclosing said protecting tube, a centrally bored connecting piece, connecting said outer tube with said holder-tube, and means for extending said protecting 70 tube for covering the cigarette.

2. In a cigarette-holder as claimed in claim 1: the outer protecting tube having a 75 longitudinal slot and a pin on the inner protecting tube projecting through said longitudinal slot of said outer protecting tube to serve as handle for said inner protecting tube.

In testimony whereof I affix my signature.

CARL SCHÖNFELD.
